UNITED STATES PATENT OFFICE.

EDWARD WESTON, OF NEWARK, NEW JERSEY.

DESIGN FOR A CASE FOR ELECTRICAL MEASURING-INSTRUMENTS.

SPECIFICATION forming part of Design No. 23,290, dated May 22, 1894.

Application filed April 13, 1894. Serial No. 507,467. Term of patent 14 years.

To all whom it may concern:

Be it known that I, EDWARD WESTON, of Newark, Essex county, New Jersey, have invented and produced a new and original 5 Design for Electrical Measuring-Instrument Cases, of which the following is a specification.

In the accompanying drawings Figure 1 is a side view of an instrument case showing 10 my design. Fig. 2 is an edge view. Fig. 3 is a section on the line 3-3 of Fig. 1, showing the conformation of the edge.

Similar letters of reference indicate like parts.

15 The leading and characteristic feature of my design is the triangular configuration of the instrument case, the said triangular figure having two straight sides and one curved side, and the face of the curved side being 20 three-sided in cross-section.

The sides of the case, one of which is shown at A, are flat and parallel. The periphery or edge of the case is much narrower in width than the side A. The said periphery shows the following portions: a straight portion, 25 B, a straight portion, C, at right angles to the straight portion B, and a circular arc, D, extending between the portions C and B. The face of the portion D is three-sided, as shown in cross-section in Fig. 3; the sides a and b 30 being inclined toward the side c, which is between them.

I claim—

The design for a case for electrical measuring instruments substantially as hereinbefore 35 shown and described.

EDWARD WESTON.
